MACHINE FOR MAKING CORN PLASTERS

**George H. Perryman, Teaneck, N. J., assignor to
The Scholl Mfg. Co., Inc., a corporation of New
York**

**Application December 30, 1932, Serial No. 649,577
Renewed May 21, 1935**

16 Claims. (Cl. 154—1)

This invention relates to an improvement in a method and machine for making corn plasters or similar articles. One of the objects of the invention is to provide a machine which will rapidly and expeditiously produce the corn plasters from several strips or webs by punching the same therefrom, and apply the corn plasters so produced on the surface of a strip or web of an open-mesh, foraminous material such as crinoline, thereafter cutting the crinoline strip into sections each of which contains as many corn plasters as may be required.

One of the obstacles encountered in corn plaster making machines in the past, has been the inability to satisfactorily work on the sticky or adhesive materials from which corn plasters are made, so that it has been practically impossible to stamp or punch the plasters from a sheet or web and force out the waste material and the plasters from the web by the punching operations. Various methods have been devised for cutting out the plasters while in the strip and then either manually picking out the center waste portions of the plasters, or else using some separate mechanical means for removing these waste elements. In such cases the production of the plasters has been greatly slowed up, and in cases where the waste portions of the plasters were manually picked out, the completion of the plasters wholly by machine operation was prevented.

My invention overcomes these and other deficiencies and defects found in present day corn plaster making machines and processes, because with my machine the materials for producing the plasters, and the backing for them, are fed into the machine and the plasters emerge from the other end in completed form, the operation of making the plasters being wholly continuous from start to finish.

40 From start to finish.
I have discovered that it is possible to punch
the plasters completely out of the strip and re-
move the waste material simultaneously with the
punching operation, by temporarily rendering the
normal sticky and adhesive material of the web
45 or strip, temporarily non-adhesive just prior to
and during the punching operations. The result
of this is that when the materials are fed to the
punch which punches out plasters and simul-
taneously removes the waste material, the strips
50 from which the plasters are formed are rendered
temporarily non-adhesive so that the punching
operation satisfactorily operates to produce the
plaster and remove the waste material simultane-
ously.

55 A further object of my invention is to provide a

machine and process for making these plasters in which the adherence of the finished plasters to their backing strip is materially improved by the removal of the moisture from the backing strip just prior to the adhesion of the plasters to the strip, and also by increasing the adhesion between the plasters and the strip by the application of heat after the plasters have been applied to said strip.

More specifically, the invention contemplates a machine in which an adhesive-faced web is fed toward a punching die. As it approaches the die, its adhesive face is rendered temporarily non-adhesive by the application of a suitable liquid. When the web reaches the die it is perforated thereby, the waste centers of the perforations being simultaneously removed by the die and forced out of the body of the web. Next, a textile fabric backing strip is adhesively attached to the perforated web so that a composite web is thus formed, out of which the annular plasters are punched and simultaneously forced out of the composite strip and into intimate contact with the face of a foraminous crinoline web which travels to a cutting device operating to sever the crinoline strip into required lengths. 10 15 20 25

In the accompanying drawings Fig. 1 is a front elevation of the improved machine; Fig. 2 is a detailed view of the intermittent driving means for one of the feed rollers; Fig. 3 is a view of several feed rollers showing how a protective covering is stripped from the web from which the corn plasters are stamped; Fig. 4 is a vertical sectional view through the machine; Fig. 5 is a sectional view through the bed plate of the machine showing two feed rollers which feed the crinoline strip with the corn plasters attached thereto toward the cutting knife; Fig. 6 is a plan view of a sheet of finished corn plasters; Fig. 7 is a sectional view through one of the plasters and the foraminous crinoline backing to which it is adhesively attached; Fig. 8 is a vertical sectional view through the cutting knife, the feed rollers for delivering the crinoline strip and attached corn plasters thereto, and the means for heating the backs of the corn plasters affixed to the crinoline strip; Fig. 9 is a plan view of the structure shown in Fig. 8 with the cutting knife removed; Fig. 10 is a sectional view on the line 10—10 of Fig. 8, looking in the direction of the arrows; Fig. 11 is a view showing the means for heating the plasters after they have been affixed to the backing strip and the adjustable support; Fig. 12 is a sectional view through the die and associated parts; Fig. 13 is a front view of the die, showing the means for clos- 50 55 60 65 70 75 80 85 90 95 100

ing an electric circuit to operate the electro-magnetic cutting knife, and Fig. 14 is a plan view of the fixed or female die and associated parts.

The corn plasters made by the method and machine herein described, are shown in detail in Figs. 6 and 7. In the form shown, each plaster is in the shape of an annulus and is usually composed of two or more layers of material. The layer shown at 10 is that which constitutes the base or body of the plaster. This layer is stamped from a continuous web or strip drawn from the roll 12 that is wound on the reel 13. The layer 14 constitutes a textile fabric backing, which has an adhesive face that affixes it to the annular member 10. This backing 14 is fed through the machine from the roll 15 and is adhesively united with the strip 11 after said strip has been perforated as will be hereafter described. The adhesive face of the annular member 10 attaches it to a strip of open-mesh starched textile fabric 16 such as crinoline, which is fed from the roll 17, wound on the reel 18, and which acts as a carrier and protective sheet for the plasters affixed to it, the plasters being sold to the user while affixed to the crinoline and subsequently stripped or peeled from the strip 16 when they are required by the user.

The plasters are thus formed from material passed through the machine in the form of three strips or webs 10, 14, and 16, and operated upon to produce the plasters, the final form of which is disclosed in Figs. 6 and 7.

The machine is provided with a suitable frame having legs 150, suitably reinforced or braced and carrying a bed plate 12 from which rises a head 20, having bearings 21 in which a crank-shaft 22 is rotatably mounted. Secured on the shaft 22 is a pulley 23 which is driven by a belt 24 extending from an electric motor or other suitable source of power. One end of the shaft 22 is provided with an eccentric or crank 25 secured to a connecting-rod 27 by a toggle 26. A clevis 28 at the lower end of the rod 27 is secured to an arm 29 extending from a housing 30 (Fig. 2) carrying rollers 32 adapted to engage a clutch element 31 and rotate it when the connecting-rod 27 moves the arm 29 in one direction. A feed roll 33 is secured on the shaft 34 mounted in bearings 62a and on which the clutch element 31 is mounted, so that through the medium of the parts just described, the feed roll is rotated with an intermittent movement.

The web 10 drawn from the reel 13 passes under the roll 33, as shown in Fig. 4, the web first passing over a tension roll 36 mounted in brackets 37 and located between the reel 13 and the feed roll 33. The roll 33 is provided with a roughened face which prevents slippage between it and the surface of the web 10. The roll 33 operates to drive other feed rolls 40 and 41 by means of a chain 42 which extends from a sprocket 43 secured on the shaft 34 of the roll 33. The chain extends over a sprocket 45 secured on the shaft 46 of the roll 40 and also over a sprocket 47 on the shaft 48 of the roll 41. Through this driving arrangement, the several feed rolls 33, 40 and 41 are intermittently rotated at the same speed and in the same direction.

Sometimes the web 10 is provided with a protective fabric covering 10a (Fig. 3) extending over its adhesive face and before the web is ready for use, it is necessary to strip the protective web 10a from the adhesive face of the web 10. The manner in which this is done is shown in Fig. 3. There the web and attached covering 10a are

shown extending from the reel 13 and passing about a roll 70 secured on brackets 71, extending upward from the base plate 72 of the machine. The protective web 10a is drawn rearwardly or toward the reel 13 and passes between the feed roll 33 and a co-operating upper feed roll 35 which draws it backward or in the direction of the arrow in Fig. 3. Springs 38, acting upon the bearings 39, in which the upper feed roll 35 is mounted, hold the roll 35 against the driven roll 33 with the web 10a fed between them. While the protective web 10a is drawn in one direction, or to the right of Fig. 3, the web 10 is drawn in an opposite direction, as indicated by the arrow a, by the rollers 41 and 73, toward the 15 punching die.

When a web 10 without a protective strip 10a is used as shown in Figs. 1 and 4 the upper feed roll 35 is not used, and is held away from the periphery of the lower feed roll 33 by a spacer 60a (Fig. 4) inserted between the bearings 39 and 62a of the respective rolls 33 and 35.

The web 10 has a sticky or adhesive face, which, as the web is fed through the machine, faces downwardly or toward the face of the lower feed roll 33. As the web is fed from between the rolls 33 and 35 and progresses toward the left of Fig. 1, its sticky under face passes over a roll 49 mounted to rotate in a trough or container 50 holding alcohol, water or some other liquid or substance 60 adapted to render the sticky or adhesive face of the web 10 temporarily non-adhesive in order to facilitate the operation of perforating this web by a die and simultaneously removing waste material from the web. The roll 49 receives liquid from the container and applies a thin layer or film of the liquid to the sticky face of the web so that when the web is fed between the movable or male member 51 and fixed or female member 52 of the punching die, it is in a temporarily non-adhesive condition and can be easily punched, and the waste centers of the openings 53 punched in the web, easily removed by the dies. The amount of liquid in the container 50 is kept constant by a feed pipe 61 extending from a suitable drip-feed valve leading from a tank containing a supply of the liquid.

After passing over the roll 49, the web 10 then extends under a guide plate 54 and between the die members 51 and 52 where the co-operating die elements 55 and 56 on the respective dies punch out a row of the apertures 53 in the strip. In punching out the apertures 53, the die elements or stud portions 55 simultaneously force the waste centers of these openings out of the body of the web and down into the chute 57 from which they pass into a suitable receptacle. Ordinarily it is almost impossible to perform this simultaneous punching and waste-removing operation with material possessing the sticky or adhesive characteristics of the material used in making corn plasters. However, due to the application of the alcohol, water or the like, which renders the sticky surface of the web relatively temporarily non-adhesive just prior to the stamping operation, the operation just described is easily performed.

The male die member 51 consists of a plate or head 62 (see Figs. 4 and 12) having the die elements or stud portions 55 extending downwardly from it and adapted to cooperate with the openings 56 in the fixed or female die 52 to punch the apertures 53 in the web 10. The die-head or plate 62 is attached to an upwardly extending 75

portion 63 movable in guides 64 in the frame head 28. A pitman 65 secured to the part 63 of the die is connected eccentrically to the shaft 22 so that the die 51 is vertically reciprocated by rotation of the shaft. Downwardly extending bosses 66 on the die head 62 are guided by studs 67 on the fixed die 52 so that the two dies are maintained in correct alignment.

After the web 10 has been perforated with the apertures or perforations 53 shown in Fig. 14, it is then adhesively united with the backing strip 14. This strip is fed from a reel containing the roll 15, supported on the bracket 86a and it extends over the feed roll 40 which is driven by the chain 42 as was heretofore explained. The roll 40 is preferably provided with a roughened face so that no material slippage between it and the backing strip 14 occurs. This backing strip has an adhesive face 14a which is uppermost as the strip passes over the roll 40. After passing over the roll 40, the strip extends downwardly around a tension roll 69 and thence passes through a slot 75 in the die-head or plate 62. The backing strip 14 then passes under a roll 16 rotatably mounted in brackets 77 extending upwardly from the fixed or female die 52. The backing strip 14 then extends substantially horizontal, and is thus brought co-extensive with the web 10 so that its adhesive face 14a is brought into intimate contact with the top or non-adhesive face of the web 10 to which it adheres, as shown in Fig. 4. The two-layer or composite strip made up of the perforated web 10 and attached backing strip 14, passes under a guide 152 and under studs or die elements 78 on the movable or male die 51, these elements 78 co-operating with complementary openings 79 in the fixed or female die 52 to stamp the annular-shaped plasters out of the composite strip and press them against the foraminous or crinoline web 16 to which they adhere and by which they are carried away to cutting means.

The strip or web 16 which receives the plasters, is fed upwardly from the reel 18 which is supported in the bracket 151 and it passes through the slot 80 in the base of the fixed die 52 and then extends horizontally over a resiliently mounted pressure pad 81. As the crinoline material 16 contains starch or some like stiffening material and is very hygroscopic it is found desirable to remove the moisture from it before the plasters are brought into adhesive contact with it to facilitate the adherence of the plasters to the strip. Accordingly, a heated plate 82 or other like heating element is mounted on the bracket 82a on the frame of the machine so that the web 16 is moved over it on its travel to the pressure plate 81. This application of heat to the web 16 serves to dry out the moisture in the web so that a perfect adherence between the plasters and the strip 16 results.

As the movable die 51 descends, the die elements or studs 78 and co-operating apertures 79 stamp out the plasters from the composite strip, composed of the layers 10 and 14, and force the plasters out of the strip and against the foraminous web 16 to which they adhere. The composite strip out of which the plasters have been punched being then waste material, passes over a roller 82 mounted in a trough or container 83 from which it receives alcohol, water or some other liquid for the purpose of rendering the perforated composite strip of waste material relatively non-adhesive so that there is no material

adherence between it and the feed rolls 41 and 13 between which it next passes. A pipe 153 leading from a drip-feed system keeps the trough 83 supplied with the liquid. The roll 73 is mounted in bearings 84 provided on the machine frame while the upper driven roll 41 is mounted in the bearings 85, spring-pressed by the springs 86 to hold the two rolls in contact. The roll 41 is driven by the chain 42 and its speed of rotation correlated with that of the rolls 33 and 40 as was heretofore described. From between the two rolls 41 and 73 the composite strip of perforated waste material, indicated at 87 in Figs. 1 and 4, extends upwardly to a take-up reel 88 (Fig. 1) on which it is wound. The reel 88 is supported on uprights 154 and is driven by a belt 89 extending from a pulley driven by a motor 90 through reducing gearing of conventional character contained in the gear box 91.

As the waste material 87 is being thus carried upwardly and away to its final disposition on the reel 88, the crinoline web 16 to which the plasters have been adhesively attached by the dies, is directed slightly downwardly and passes between a pair of feed rolls 92 and 93. The lower feed roll 92 is the driven roll, having a shaft 94 carrying a ratchet 95 that is engaged by a pawl 96 pivotally mounted on a link 97 which has one of its ends loose on the shaft 94 and its other end pivotally connected to the lower end of a connecting rod 98. At its upper end, the connecting rod 98 is connected by a toggle 99 to an eccentrically disposed pin or crank 100 on the drive shaft 22. As the shaft 22 is rotated, the connecting rod 98 and the intermittent drive mechanism just described, intermittently rotates the roll 92 so that the same in cooperation with its companion roll 93 feeds the crinoline and the plasters attached thereto toward a cutting device to be described. By the use of different ratchets in place of that shown at 95, the length of each section of crinoline and resultantly the number of plasters borne by each cut section is regulated. For example, in Fig. 6 a severed strip of crinoline bearing a dozen plasters is shown. By arrangement of the notches in the ratchet 95 the pauses in the feeding of the crinoline strip may be regulated so that the severance of the strip may be had in any desired lengths, as will be readily understood. The shaft 94 of the roller 92 carries a gear 155 which meshes with and drives a gear 156 on the shaft of the upper roller 93. Said roller 93 contacts with the strip 16 only at its longitudinal edges, as will be seen in Fig. 5, so that pressure on the plasters by the rollers is avoided. A brake 157 of conventional construction, embraces the shaft 94.

After the crinoline strip 16 bearing the plasters passes between the two feed rolls 92 and 93, it is moved under a heater in the form of a plate 60 or like element 101 which applies heat to the backs of the plasters secured on the crinoline strip and serves to intimately and firmly attach them to the crinoline, at the same time fully drying out the alcohol or other liquid previously applied for the purpose of rendering the sticky faces of the strip from which the plasters were formed temporarily non-adhesive.

The heater 101 is supported by a yoke 102 (see Fig. 11) provided with a vertical lug 103 having its upper end pivoted at 104 on the end of a lever 105 fulcrumed at 106 in an upright 107 extending upwardly from the base plate 72 of the machine. The edge of the lever 105 is provided with a series of notches 108, any one of which is adapted to

be engaged by a pin 109 in the end of an arm 110 which has its opposite end pivotally attached to the upper end of the upright 107. A spring 111 connects the heater with a stud 112 on the upright and acts to hold the heater properly positioned over the crinoline web and attached plasters. Through the arrangement by which the heater is suspended, the degree of pressure by it on the web may be adjusted, and the heater may be easily 10 raised at any time during accidental machine stoppage to avoid singeing or burning the plasters then positioned beneath it.

From beneath the heater 101 the crinoline strip and attached plasters next pass between two feed 15 rolls 113 and 114 by which the strip and plasters are fed to the cutting knife indicated at 122. The lower feed roll 113 is mounted in bearings 115 extending upwardly from the base plate 72 and it is driven by a belt 116 extending from the 20 pulley 117 driven by the gearing in the gear case 91. The shaft 158 of the roll 113 carries a pulley 118 about which the belt 116 extends. The upper roll 114 is mounted in the movable bearings 119 and is urged toward its companion roll 113 by 25 the springs 120. A gear 159 secured on the shaft 158 meshes with and drives a similar gear 160 secured on the shaft of the upper roll 114 so that the two rolls are rotated together. The roll 114 is centrally hollowed and thus grips the crinoline 30 web 16 only adjacent its ends and at the longitudinal edges of the web so that pressure of the plasters between the two rolls is avoided. After passing between the two rolls 113 and 114, the web 16 and attached plasters are fed through 35 edge guides 121 which present it to the cutting knife 122. The knife 122 is carried on a cross-head 123 provided with guides 124 which slide on vertical rods 125 connected by the cross-piece 126. A vertical rod 127 extends upwardly from 40 the cross-head 123 and is connected to or else forms the core 128, of an electro-magnet 129, the conventional windings of which are shown at 130. This magnet is connected to a suitable source of electric current and is energized 45 intermittently to cause the knife 122 to be forced downwardly to sever a section of the crinoline strip bearing a required number of the plasters. Springs 131 extending between the cross-head 123 and the cross-piece 126 normally hold the 50 knife raised while the circuit to the magnet is broken. The knife 122 on its descent co-operates with a shoulder 161 on a supporting plate 162 to sever the strip into lengths. A plate 163 extending diagonally outward from one of the 55 guides 121 and overlying the strip 16, prevents the strip from rising upward upon the ascent of the knife.

The means for closing circuit to the magnet is shown in detail in Figs. 12 to 14 inclusive. On 60 its rear edge, the movable die head 62 carries a downwardly extending plate 132, adapted upon the descent of the die, to impinge against a pin 133 projecting laterally from a rocking lever 134 closely mounted on a stud shaft 135 rotatably 65 supported in the bracket 136. At its other end, the lever 134 carries a pawl 137 adapted to engage a ratchet 138 secured on the shaft 135. Secured on the shaft 135 is a cam 139, which in the form shown, is square in cross section. Each of the 70 four corners or edges 140 of the cam successively operates against a spring contact 141 and causes it to close circuit with another contact 142 which resultantly closes the electric circuit to the magnet, causing the knife 122 to descend and cut off 75 a section of the crinoline strip. The timing of

the feed mechanism and the descent of the knife are so correlated that the cut occurs between the rows of plasters on the strip. By the shape of the ratchet 95 and the shape of the cam 139, the length of the strip cut, and resultantly the 5 amount of plasters on each severed strip, is regulated.

In some instances, it may be found desirable to cut single rows of plasters from the strip. In such a case, the simple circuit-closing arrangement shown to the left of Fig. 13 for the magnetic knife, may be used rather than that heretofore described. In this arrangement the die plate or head 62 carries a dependent rod 144, which, on each descent of the die head contacts 15 with a spring contact 145 causing it to close circuit with another contact 146 and thus energize the magnet. When this switch, consisting of the contacts 145 and 146, is connected in the magnet circuit, the other switch composed of the elements 141 and 143, is removed from the circuit.

Briefly, the operation of the machine is as follows:

The web 16, fed from the reel 13 extends under the feed roll 33 (or between the rolls 33 and 35 as shown in Fig. 3) and then passes over the moistening roll 49 which applies a thin film of liquid to the sticky face of the web, acting to render this face of the web temporarily non-adhesive. When the part of the web which has 30 been so moistened reaches a position between the dies 51 and 52, the movable or upper die 51 descends, during a pause in the intermittent feed of the strip, and punches a row of the perforations 53 in the strip, at the same time forcing the 35 waste centers 53a (Fig. 14) bodily out of the strip and down into the chute 57. The backing strip 14 coming downwardly through the transverse slot 75 in the die head 62 moves co-extensively with the now perforated web 16 and adheres to the upper face of the same, covering the 40 perforations 53 formed therein. The die elements 78, co-operating with the complementary openings 79, stamp out the annular corn plasters from the composite web made up of the 45 adhesively united web 16 and strip 14. These plasters are forced bodily out of the composite strip and downwardly against the face of the warmed and dried crinoline web 16 by the die elements 78, and they adhere to said strip and are carried 50 along on it. The composite strip shown at 87 is now waste material and it passes over a moistening roll 82 which moistens its adhesive face and it then passes between the feed rolls 41 and 45 55 which feed it to the driven take-up reel 88 on which it is wound. In the meantime, the strip 16 of crinoline, carrying the attached plasters are fed by the intermittently rotated feed rolls 92 and 93 toward the cutting knife 122. On 60 its way to the cutting knife, the strip 16 passes under the heater 101 so that the backs of the plasters on the strip are brought into contact with the heater which acts to dry out the previously applied liquid and serves to firmly affix the plasters to the strip. From between the rolls 113 and 114, the strip 16 is fed to the intermittently operating knife 122 which severs it into 65 sections, each of which bears a certain number of the affixed plasters. The cut sections descend on the slide 170 into a suitable receptacle. 70

In herein describing the operation of the machine, I have described it in connection with the manufacture of a certain type of representative corn plaster. However, I do not wish to be understood as limiting the invention to a machine 75

and method for manufacturing that specific type, since there are several different types of corn plasters and other protective pads which can be easily manufactured by the machine and method herein described.

5 What I claim is:

1. A machine of the class described having means for feeding a web composed of a textile fabric provided with a sticky surface, means for temporarily rendering the sticky surface of said web relatively non-adhesive, means for perforating the web while it is in its relatively non-adhesive condition and forcing waste material out of the perforations, means for adhesively uniting a fabric backing to the back of the perforated web to form a composite web, means for punching plasters out of the composite web and simultaneously forcing said plasters out of the web, means for feeding a foraminous web adjacent to the composite web so that the punched-out plasters are directed against the foraminous web by the punching operation, a heater, means for carrying the backs of the plasters against said heater while the plasters are attached to the 25 foraminous web, and means for severing the foraminous web into lengths.

2. In a machine of the class described, means for feeding a fabric web having a sticky surface, means for punching corn plasters out of said web, and means for rendering the sticky surface of the web relatively non-adhesive before the web is fed to the punching means.

3. In a machine of the class described, means for feeding a fabric web having a sticky surface, 35 means for punching corn plasters out of said web, means for rendering the sticky surface of the web relatively non-adhesive before the web is fed to the punching means and means for restoring adhesiveness to the plasters after they have been 40 punched out of the web.

4. In a machine of the class described, means for feeding a fabric web having a sticky surface, means for punching corn plasters out of said web, and means for applying a liquid to the sticky 45 surface of said web to render said surface relatively non-adhesive before the web is fed to the punching means.

5. In a machine of the class described, means for feeding a fabric web having a sticky surface, 50 means for punching corn plasters out of said web, means for applying a liquid to the sticky surface of said web to render it relatively non-adhesive before the web is fed to the punching means and means for applying heat to the punched-out plasters to restore adhesiveness thereto.

6. In a machine for making corn plasters and the like, means for feeding three fabric webs, 55 means for perforating one of the webs, means for adhesively uniting it with a second web after it has been perforated, means for punching out corn plasters from the two webs thus united and simultaneously forcing them out of the two united webs and directly into contact with the third web to adhesively affix them thereto.

7. In a machine for making corn plasters and the like, means for feeding three fabric webs, 60 one of which is provided with a sticky surface, means for applying a liquid to said surface to render it temporarily non-adhesive, means for perforating said web and simultaneously forcing the waste centers out of the perforations, means for uniting said perforated web with a second web, means for punching out corn plasters from 70 the two webs thus united and simultaneously

forcing the plasters out of the body of the two united webs and directly into contact with the third web to adhesively affix them thereto, and means for heating the plasters while they are carried on the third web.

8. In a machine of the class described, means for adhesively uniting a perforated web and an imperforate web, punching dies, means for moving the united webs between the dies to cause plasters to be stamped out of them and forced by the dies against the face of a web of foraminous material to cause them to adhere thereto.

9. In a machine of the class described, means for feeding a web composed of textile fabric provided with a sticky surface, means for moistening the sticky surface of the web to render it relatively non-adhesive, means for punching groups of perforations in the web and simultaneously forcing waste material out of the perforations and away from the web, means for adhesively applying a textile fabric backing over 15 the back of the web, means for punching out plasters from the composite web thus formed and simultaneously forcing the punched-out plasters out of and away from the composite web, means for feeding a foraminous fabric web co-extensively 20 with the composite web so that the punched-out plasters are adhesively applied to said foraminous fabric by the punching dies, and means for severing the foraminous fabric web into lengths. 25

10. In a machine of the class described, means for feeding a web of foraminous material, means for stamping plasters of adhesive material into contact with a face of the web, and means for heating the web as it is being fed to plaster-receiving position thereby to drive out moisture 30 from the web and aid in causing adhesion of the plasters to the web.

11. In a machine of the class described, means for feeding a web composed of textile fabric provided with a sticky surface, means for moistening the sticky surface of the web to render it relatively non-adhesive, means for punching groups of perforations in the web and simultaneously forcing waste material out of the perforations 45 while the sticky surface of the web is in a relatively non-adhesive condition, means for adhesively applying a textile fabric backing over the back of the perforated web, means for punching out annular plasters from the composite web thus 50 formed and simultaneously forcing the punched out plasters out of and away from the composite web, means for feeding a foraminous fabric web co-extensively with the composite web so that the punched-out plasters are adhesively applied to 55 said foraminous fabric by the punching dies, means for severing the foraminous fabric web into lengths, and means for heating the plasters carried by said web.

12. A machine of the class described having 60 means for feeding a web composed of a textile fabric provided with a sticky surface, means for moistening the sticky surface of the web to render said surface relatively temporarily non-adhesive, a die for perforating the web while said web is in 65 its relative non-adhesive condition and forcing waste material out of the perforations simultaneously with the perforating operation, means for feeding a second web having a sticky surface so that said second web overlies the back of the 70 perforated web and is adhesively attached thereto, punch elements carried by the die for punching plasters out of the composite web and forcing said plasters bodily out of the web, and means for feeding a foraminous web relative to the die 75

- so that the plasters punched out by the punch elements thereon are directly applied against the face of the foraminous web.
13. In a machine of the class described, means for moistening the surface of a sticky-faced fabric to render its normally sticky surface temporarily relatively non-adhesive, and means for stamping plasters bodily out of and forcing them away from the fabric while it is in a non-adhesive condition.
14. In a machine of the class described, means for moistening the surface of a sticky-faced fabric to render its normally sticky surface temporarily relatively non-adhesive, dies for stamping plasters bodily out of and forcing them away from the fabric while it is in a non-adhesive condition, and means for restoring adhesiveness to the plasters after they have been stamped out.
15. In a machine of the class described, means for rendering the surface of a sticky-faced fabric temporarily and relatively non-adhesive, and means for stamping plasters out of and forcing them bodily away from the fabric while it is in such non-adhesive condition.
16. In a machine of the class described, means for feeding a starched foraminous web into position to receive adhesive-surfaced plasters, means for pressing such plasters into contact with one face of said web, and a heater acting upon the opposite face of said web being fed for driving moisture from said web and aiding in causing adherence of said plasters to said web.
